JOHN P. WEIS, OF NYACK, NEW YORK, ASSIGNOR TO LUCIUS N. LITTAUER, OF GLOVERSVILLE, NEW YORK.

TRIMMING MECHANISM FOR SEWING-MACHINES.

1,016,590.

Specification of Letters Patent.

Patented Feb. 6, 1912.

Original application filed July 13, 1909, Serial No. 507,368. Divided and this application filed December 29, 1910. Serial No. 599,796.

To all whom it may concern:

Be it known that I, JOHN P. WEIS, a citizen of the United States, residing in Nyack, county of Rockland, and State of New York, 5 have invented a new and useful Improvement in Trimming Mechanism for Sewing-Machines, of which the following is a description.

My invention relates to sewing machines 10 of the type in which trimming, binding and sewing are done simultaneously.

Particularly, my invention relates to trimming mechanism by which the work is trimmed preparatory to binding and stitching 15 the binding to the work, whether the latter be woven, knitted, or otherwise produced.

My invention is especially useful on machines for binding knit-goods, or loosely- 20 woven fabric, because such materials stretch excessively under the action of the feed and during the application of the binding and also because they ordinarily present a ragged, uneven and rough edge which, if 25 not previously disposed of, will give to the binding, when applied, a bulky, uneven and distorted appearance. With these conditions of the work, difficulty has been found in mechanically applying the binding evenly 30 and smoothly and in a manner to overcome the tendency of the material and binding to pucker or stretch relatively and avoid the uneven and bulky appearance of the edge of the work after the binding is applied.

It is, therefore, among the objects of my 35 invention to provide certain novel features of construction and combinations of elements which, in the machine, will operate and coöperate to trim the edge of the work 40 uniformly and accurately, during the progress of the body-fabric and binding; and to dispose of the trimming so that it will not interfere with the work or the stitch-forming mechanism.

With these and other objects in view, 45 which will be clearly set forth during the course of the description, my invention consists in certain elements and combinations of elements, devices and features of construction, all as hereinafter fully set forth 50 and particularly referred to in the claims.

In the drawings, forming part of this description: Figure 1 is a top-plan view of the cloth-plate and a horizontal section of

the vertical arm of a sewing machine to 55 which my invention has been applied; Fig. 2 is a side elevation of Fig. 1; Fig. 3 is a transverse vertical section of the machine taken just to the right, in Fig. 2, of the trimmer-blade, or substantially centrally of 60 the trimming mechanism; Fig. 4 is a perspective view of the guard-plate; and Fig. 5 is a perspective view of the trimmer-blade and its attached shunt-guide.

In the drawings, the numeral 1 indicates 65 the bed-plate of the machine, 2 the vertical arm thereof, which is extended into an overhanging-arm, carrying at its forward end, as usual, the head in which the needle-bar 3 and presser-bar 4 have their bearing, 70 the needle-bar having a vertically-recipro- cating movement, as usual, from the vibratory lever, having the depending-arm 5, connected by pitman 6, to the looper 7 of the machine.

The driving-shaft 8 extends longitudinally of the machine, and actuates the feeding mechanism, the parts of which are indicated by 9. These parts, together with the needle 10, presser - foot 11, cloth - plate 12, 75 throat - plate 13, slide - plate 14, carrying binder 15 and guides 16, are all, or may be, the same as similar parts shown in my pending application Serial Number 507,368, filed July 13, 1909, of which this case is a division. 80

The trimming mechanism is arranged so as to trim the edge of the body material not only in advance of the stitching, but also in advance of the application of the binding 90 to the edge of the body material, the trimmer and ledger blades, in consequence, being arranged in front of the binder, as clearly shown in Figs. 1 and 3.

The trimming mechanism, in its general 95 structure and its mode of application to the machine, is, in all material respects, substantially the same as that disclosed in my pending application Serial No. 279,116, filed September 19, 1905, and, in consequence, a detailed description will not here be given; but the various parts, which are features of the trimming mechanism of my said application, and which are necessary to an understanding 100 of my present invention, will be presently described. One of the important features of my present construction resides in the addition of a diverter 18, for the trim- 105

ming which is cut from the edge of the body-material, to the upper arm 19 of the trimmer-lever, said lever having, at its forward end, the trimmer-blade, extending at a right-angle thereto, of the same form as in my last said pending application. The diverter extends horizontally along the length of the trimmer-arm 19 and conforms substantially to the shape thereof and is vertically turned 10 or upturned at its rear end to produce the diverter-portion 20, at the upper end of which is the overhanging-guard 21, which prevents the trimming from rising and running over the diverter-portion. An important 15 feature of this construction resides in the fact that the diverter, thus combined with the trimming mechanism, can be quickly removed from the machine and disposed of when the trimmer is removed; and the particular 20 advantage of having it connected to the trimmer-arm is that when, during the operation of the machine, it is desired to stop the trimming action of the trimmer-blade, the latter, together with the diverter, 25 can be quickly depressed below the cloth-plate of the machine by the mechanism illustrated in Figs. 2 and 3 and fully set forth in my aforesaid application, Serial No. 279,116. This mechanism generally speaking 30 consists of the eccentric 30 surrounded by the strap 31, the tubular extension 32 of which receives within it the rod 33 pivoted at 34 to the lower end of the bell-crank lever 17 journaled at 35 to the removable bracket 36 and the horizontal arm 19 of which lever carries the diverter 18. A latch lever 37 carried by the journal 34 couples the rod 33 with the tubular extension 32 so as to make the two act as one under the influence of the 40 eccentric 30. When it is desired to throw the trimming mechanism out of operation the lever 37 is unlatched, thus breaking the coupling or connection between the members 32 and 33 and preventing the eccentric 30 from actuating the bell-crank lever 17—19. 45 When this occurs, the diverter and the cutting-blade of the trimmer are depressed so that the cutting-blade has no function; and it requires only that the rod 33 be pressed 50 into the extension 32 and the latch-lever 37 reset, in order to again set the trimmer and diverter into operation. All this is more fully set forth in my aforesaid application. Another important feature is that, by connecting the diverter to the trimmer-arm, said 55 diverter is kept in constant vibration during the trimming operation, resulting in keeping the "trimming" constantly in movement and causing the same to be gradually carried away from the trimmer-arm and over to the shunt-guide and guard-plate shown in. 60 Fig. 4. This keeps the diverter free from being crowded with the "trimming" and also keeps the diverter free from lint, since 65 the agitation or vibration of said diverter

will cause the lint to also be carried over to the shunt-guide and guard-plate. This has the important advantage also of keeping the driving-shaft and other parts, located below the cloth-plate, quite free from lint, which, 70 in the present machines, ultimately clogs the mechanism and retards the free and rapid action of the machine.

The coöperating shunt-guide and guard shown in Fig. 4 consist of a plate having the longitudinal, outwardly-deflected, lower portion 22, which extends to the bottom of the bed-plate, and, above the same, a substantially vertical portion 23, provided at its opposite ends with the longitudinal slots 24, 80 through which attaching-screws 25 are passed and which are screwed into the front edge of the bed-plate, as shown in Fig. 2, the slots permitting adjustment of the said plate lengthwise of the machine. Above the 85 said vertical portion 23, the guard is formed concaved to its top edge, as shown at 26. These features constitute the guard-portion of the plate, since they prevent lint, dust and other substances from reaching the operating mechanism of the machine at this point and prevent the work from engaging said mechanism and the latter from throwing oil upon the work. The shunt-guide portion of the plate comprises the inclined part 27, connecting at its lower end with the concaved portion 26, and having at its upper end the substantially horizontal ledge 28, extending rearwardly to the vertical portion 29, which forms a continuation of the concaved portion 26 of the plate. With the plate thus constructed, and in the position shown in Fig. 2, the "trimming" of the body material will be cast over onto the diverter 18 and the vibration of the latter will cause 95 said trimming to be gradually and continuously moved, together with all lint produced during the operation of the machine, over to the shunt-guide, down the inclined surface of which said trimming and lint will 100 rapidly pass and will be deflected away from the machine by the outwardly-turned, lower portion 22 of said guard-plate.

From the foregoing description, but a brief statement of the mode of operation 115 will be necessary and, principally, it should be understood that, if knit-goods are operated upon and a differential movement is given to the feeding mechanism, the body-material will be fed up to the trimmer, past the binder and to stitching position by the differential feed-dog, the binding being applied to the edge of the body-material by the binder, and the binding stitched in place. The two materials, as thus combined, will be 120 fed away from the stitching position. As the body-material is fed into and through the machine, if the trimmer is in operation, the edge thereof will be evenly trimmed and the trimming will naturally fall to the right 125 130

side upon the diverter, the rapid vibration of which will carry said trimming, together with lint which may be produced, directly over onto the shunt-guide and thence down 5 the incline thereof to the bottom of the concaved portion 47 of the guard-plate, and thence to the floor, or into a "catch-all," which may be supplied for the purpose.

An important feature of my invention re-
10 sides in the fact that, at any time during the stitching and binding, trimming of the body-material can be carried on in advance of the stitching and binding and can be omitted at the will of the operator in order 15 to produce special work. Other important features and combinations will have stress laid upon them by being mentioned, both broadly and specifically, in the claims.

Having thus described my invention, what 20 I claim and desire to secure by Letters Patent is:

1. The combination in a trimming mechanism, of a ledger-blade, a vibratory arm, a trimmer-blade carried by said arm at a 25 right-angle thereto, a diverter extending along the length of the arm and of the blade, thus providing a guard portion co-operating with said trimmer-blade and a receiving portion co-operating with said arm 30 for receiving the trimming of the work.

2. In combination, a trimming mechanism including a vibratory blade, a diverter attached to the vibratory blade, and means whereby the trimmer and the diverter may 35 be thrown into and out of action at the will of the operator during the running of the machine and without disturbing the action of the latter.

3. In combination, a trimming device, a 40 diverter for the trimmed edge of the material comprising a horizontally disposed plate terminating in an upturned portion and an overhanging guard, and means whereby the diverter may be vibrated so as 45 to cause the said trimmed edge to be carried away from the trimming device.

4. In combination, a trimming mechanism, a horizontally arranged diverter, a shunt-guide, having a ledge, and means for 50 vibrating the diverter whereby the trimming of the work will be caused to travel

laterally away from the trimming mechanism, into co-operation with the shunt-guide and over the ledge thereof.

5. In combination, a trimming device, a 55 diverter for the trimmed edge of the material, and means whereby the diverter may be thrown into and out of operative position at the will of the operator during the running of the machine and without disturbing the action of the latter.

6. In combination, a trimming mechanism including a vibratory blade, a vibratory diverter co-operating with said blade, and means whereby the trimmer and the diverter may be thrown into and out of action at the will of the operator during the running of the machine and without disturbing the action of the latter.

7. In combination, a trimming mechanism, a horizontal vibratory diverter arranged at one side of the trimming-blades of said mechanism, a stationary shunt-guide arranged below the diverter in co-operative relation to the latter, and a guard co-operating 75 with the shunt-guide and diverter, substantially as described.

8. In combination, a trimming mechanism, a horizontal vibratory diverter arranged at one side of the trimming-blades 80 of said mechanism, said diverter having an overhanging guard co-operating with one of said blades, and a shunt-guide co-operating with the diverter, the latter and shunt-guide acting to carry the trimming away from the 85 trimming-blades.

9. In combination, a trimming mechanism, a horizontal vibratory diverter co-operating with the trimming mechanism, a shunt-guide arranged under the diverter at 90 one side thereof for receiving the trimming from the latter, and a guard carried by the shunt-guide and co-operating with the diverter, substantially as described.

In testimony whereof I have hereunto 95 signed my name in the presence of two subscribing witnesses.

JOHN P. WEIS.
